UNITED STATES PATENT OFFICE.

WILLIAM MITCHELL, OF DETROIT, MICHIGAN.

METHOD OF FORMING REINFORCED CONCRETE STRUCTURAL MEMBERS.

Application filed April 2, 1919. Serial No. 288,988.

To all whom it may concern:

Be it known that I, WILLIAM MITCHELL, a citizen of the United States of America, residing at Detroit, in the county of Wayne 5 and State of Michigan, have invented certain new and useful Improvements in Methods of Forming Reinforced Concrete Structural Members, of which the following is a specification, reference being had there- 10 in to the accompanying drawings.

The invention relates to reinforced concrete structural members and the method of forming the same. One object of the invention is to provide a construction which can 15 be readily and cheaply manufactured and can take the place of reinforced concrete constructions, in which it is necessary to erect false-work for holding the cement while in plastic condition. Another object 20 is the provision of a construction in which the sides of the metallic reinforcing member are coated with cement to completely encase the reinforcing member; and further, to shape to a container or hollow form the 25 metallic reinforcing member and coat the inside and outside of the same with cement so as to form a container in which plastic concrete may be poured and by which it will be retained until hardened. A further ob- 30 ject is to provide hollow constructions which can be assembled in relation to each other and then filled with plastic concrete. Other features of the invention reside in the method of forming the reinforcing concrete struc- 35 tural members, in their assembly and filling, and in further advantages as more fully hereinafter set forth.

In the drawings:

Figure 1 is a perspective view of a reen- 40 forced concrete structural member embodying my invention;

Figure 2 is a similar view of a modified construction;

Figures 3, 4 and 5 are cross-sections of 45 other modified constructions;

Figure 6 is a cross-section on the line 6-6 of Figure 4;

Figure 7 is a perspective view, with parts 50 broken away, showing an assembly of some of the reinforced structural members;

Figure 8 is a cross-section through a portion of modified construction.

As shown in Figure 1, 1 is a metallic re- 55 inforcing member having a series of apertures or meshes therein, such as metal lath, which is coated with cement by drawing the

same through a bath of plastic cement. This plastic cement extends through and closes the apertures or spaces in the reinforcing member and forms coatings or layers 60 2 on its sides to completely encase the same. Before hardening of the coatings the surfaces of either one or both are suitably finished so that the structure is finished and ready to be used after the cement has sufficiently hardened. This construction is 65 adapted for use particularly as siding upon a building. Another method of coating the reinforcing member is to place the same into a mold and pour the plastic cement into the mold to coat both sides and pass through the apertures therein.

Figure 2 shows an apertured reinforcing member 3 bent into a channel shape and then coated outside and inside with cement by drawing the same through a bath of plastic cement, which cement extends through the frame or reinforcing member and forms coatings or layers 4 to completely encase the reinforcing member. This cement, when hardened, forms an impervious construction which may be used in various ways, such as beams, etc. If desired, these beams can be filled with concrete after being placed in correct position and the plastic concrete when poured into this channel-shaped beam will be retained thereby and allowed to harden therein to form a strong and substantial construction without the necessity of erecting false-work for holding the 85 plastic concrete until it is hardened.

Figure 3 discloses another modified construction in which the reinforcing member 5 is so formed that its sides encloses a rectangular space. This reinforcing member is 90 encased by integral coatings of cement 6 by the same method as above described. This construction may be used as a wall section and can be strengthened by connecting the ends of the reinforcing member 5 intermediate the sides before the same are coated by means of a suitable reinforcing strip 7, and then coating all the sides by the above method. To make the construction still 95 stronger, plastic concrete 8 may be poured into one of the spaces between the intermediate partition and one of the sides, where it will be contained until hardened, the other space remaining empty so that an air space 100 will be formed in the section.

As shown in Figure 4, 10 is a column having the base 11, central portion 12 and top 110

13. The base 11 has the apertured reinforcing member 14 which is of substantially the same contour as the outer surface of the cement coated thereon by the above method. This base is filled with concrete, thereby making a solid construction. The central portion 12 has the apertured metallic reinforcing member 15, which has the coats 16 upon its inside and outside which are 10 formed as above described. The top 13 has the metallic reinforcing 17 which, when the top is placed upon the central portion 12, is in substantial alignment with the reinforcing 15 of the central portion. 18 is a metallic reinforcing member extending outwardly and upwardly away from the lower edge of the reinforcing 17. This reinforcing 18 has substantially the same form as the outer contour of the coating of cement 16 20 encasing the reinforcing members.

In erecting the column the base 11 is set up and the central portion 12 placed upon the base and then the top portion 13 placed upon the central portion. If it is desired 25 to strengthen the column, plastic concrete is poured through the aperture in the top portion to fill the space within the central portion 12, as well as the central portion within the top, wall ties 20 being provided 30 for more securely tying the concrete to the shell formed by the reinforcing with its coatings of cement. This concrete does not enter the space between the upright and outwardly and upwardly flaring walls of the 35 top.

In order to produce the desired contour of the base 11 and top 13, the outer coatings of cement are suitably formed before the cement has hardened, preferably by 40 scraping off part of the outer coating before hardening thereof to produce the desired curves.

As shown in Figure 6, the reinforcing used may be provided with projections 21, 45 which are not apertured, thereby strengthening the construction.

If it is desired to produce constructions having recesses therein of greater depth than would be permitted by one coating of cement upon the reinforcing, the construction 50 may be given a desired number of coatings by passing the same through a number of baths after permitting the preceding coating to slightly harden. This is shown in Figure 55 5 where 22 is the reinforcing, 23 are the first coatings upon the inside and outside of the reinforcing and 24 are the second coatings upon the inside and outside of the previous coatings 23, which coatings are formed 60 by the above method. 25 are recesses formed outside the reinforcing 22, these recesses being in the present instances flutings in a column. In order to produce an external finished construction, the surfaces 65 of the outer coatings are shaped and finished

before hardening, so that it is not necessary to finish the same after erection.

From the above, as thus far described, it will be readily seen that I have provided a simple method of forming reenforced concrete structural members in which the reinforcing is coated on its sides, as by passing the reinforcing through a bath of plastic cement, or by casting the cement around the reinforcing. Furthermore, these coatings of cement close the apertures in the reinforcing and form an impervious construction which is adapted to retain plastic concrete without permitting the escape of the cementitious liquid in this concrete. Due to 70 this construction, it is not necessary to erect false-work to retain the plastic concrete. Furthermore, the structure formed has material advantages over constructions formed by the previous methods. Due to the cement and metallic reinforcing being closely bonded the construction is very strong so that the quantity of reinforcing and concrete is considerably decreased. Furthermore, the surface of the outer coating being 75 finished during the manufacture, it is not necessary to plaster or otherwise finish the same after erection of the structure.

A very important feature of the invention resides in the structure shown in Figure 7, wherein 26 is a hollow reenforced cement column. 27 are hollow reenforced cement beams of channel shape extending between and resting upon the upper ends of the columns 26. 28 are hollow reenforced cement 100 floor sections of channel or U-shape which extend between parallel-extending beams 27 and are mounted thereon. Specifically, these floor sections have the upwardly-extending flanges 29 at their ends which terminate in laterally-extending flanges 30 which rest upon the upper edges of the beams 27. These columns, beams and floor sections are formed by the above method and, when assembled, form series of impervious shells, 105 which are adapted to contain plastic concrete poured thereinto without the necessity of using false-work. This plastic concrete is continuous so that in effect a monolithic building construction is secured for each 110 floor.

As shown in the modified construction in Figure 8, the beam 31 is of more rounding shape and the flanges 32 at the ends of the floor sections 33 extend upwardly and outwardly and conform to the outer curvature of the upper portion of the beams.

It will readily be seen from the above descriptions that I have provided hollow reenforced structural forms which may be 115 readily assembled in relation to each other and which, when assembled, are adapted to contain plastic concrete which will continuously form the floor sections and beams and extend through the column. This construc- 120 130

tion and the method of building is highly advantageous inasmuch as the building may be more readily and cheaply manufactured and, furthermore, consume less time, since the columns, beams, floor sections and any other necessary sections may be brought to the place of assembly and assembled immediately. The outer surfaces of these sections are finished before assembly, which also

10 facilitates the construction of the building.

What I claim as my invention is:

1. The method of forming a reenforced structural member which consists in first shaping the member and subsequently passing said member through a bath of plastic cement to completely encase said member.

2. The method of forming a reenforced structural member, comprising the bending of an apertured reinforcing member to hollow shape, the passing of the member through a bath of cement to fill the apertures of and coat the same to form an impervious construction.

3. The method of forming a reenforced concrete structural member, comprising the bending of an apertured reinforcing member to hollow shape, the passing of the member through plastic cement to fill the apertures of and coat the inside and outside thereof, the allowing of the hardening of the cement to form an impervious hollow unit construction, and the filling of the hollow member with plastic concrete.

4. The method of forming a reenforced concrete structural member, comprising the forming of an apertured reinforcing member to enclose a space, the passing of the member through plastic cement to coat the inside and outside thereof, the allowing of the hardening of the cement upon the member to form an impervious reenforced shell, and the filling of the space in the shell with plastic concrete.

In testimony whereof I affix my signature.

WILLIAM MITCHELL.
